UNITED STATES PATENT OFFICE.

WILLIAM W. DUDLEY, OF LANCASTER, PENNSYLVANIA.

DESIGN FOR A MOVEMENT-FRAME FOR WATCHES.

53,492.

Specification for Design.

Patented July 8, 1919.

Application filed July 19, 1918. Serial No. 245,767. Term of patent 7 years.

To all whom it may concern:

Be it known that I, WILLIAM W. DUDLEY, a citizen of the United States, residing at Lancaster, in the county of Lancaster and State of Pennsylvania, have invented a new, original, and ornamental Design for a Movement-Frame for Watches, of which the following is a specification, reference being had to the accompanying drawing, forming part thereof.

The figure is a plan view of the back of a watch movement, showing my new design.

My design consists in the employment of symbols of the Masonic order for the decoration of watches, which, as shown in the drawing, are used at the back of the movement as bridges, the shapes or forms of which are those of said symbols.

I claim:—

The ornamental design for a movement frame for watches, as shown and described.

WILLIAM W. DUDLEY.
